UNITED STATES PATENT OFFICE.

CHARLES F. NYQUIST, OF BUCYRUS, OHIO.

DEVICE FOR LOCATING SUNKEN VESSELS.

1,188,308.

Specification of Letters Patent. Patented June 20, 1916.

Application filed February 1, 1916. Serial No. 75,598.

To all whom it may concern:

Be it known that I, CHARLES F. NYQUIST, a citizen of the United States, residing at Bucyrus, in the county of Crawford, State of Ohio, have invented certain new and useful Improvements in Devices for Locating Sunken Vessels; and I do hereby declare the following to be a full, clear, and exact description of the invention, such as will enable others skilled in the art to which it 10 pertains to make and use the same.

The present invention is directed to improvements in devices for locating disabled submarine vessels, and has for its object to 15 provide a device of this character which can be released by the crew, whereby the position of the sunken vessel can be ascertained.

A further object of the invention is to provide a device of this character which 20 when released upon sinking or disabling of the vessel, can be distinguished upon the surface of the water, and further to provide a device so constructed as to be seen at day or night.

25 A still further object of the invention is to provide a device of this character which will permit a rescue crew to carry on a conversation with the crew of the sunken vessel.

With these and other objects in view, this 30 invention resides in the novel features of construction, formation, combination and arrangement of parts to be hereinafter more fully described, claimed and illustrated in the accompanying drawing, in which:—

35 Figure 1 is a fragmentary sectional view of a vessel, showing the device released. Fig. 2 is a sectional view on line 2—2 of Fig. 1. Fig. 3 is a sectional view on line 3—3 of Fig. 2. Fig. 4 is a detail sectional 40 view through the float.

Referring to the drawing 1 designates a section of the vessel, on the floor of which is mounted a pair of spaced bearings 2, which rotatably support the shaft 3. Slidably feathered on the shaft is a drum 4, which has wound thereon an electric conducting cable 5, which passes through the stuffing box 6, said stuffing box being attached to the deck of the vessel and is aligned 45 with the opening 7 formed in the bottom of the holder 8, which is supported by the deck of the vessel, whereby said cable can be attached to the coupling 9. The coupling 9 is connected to the float 10, in which is located a telephone 11, and the incandescent lamps 12, said lamps being arranged ad-

jacent the bull's eyes 13, which may be of any suitable colored glass.

The shaft 3 is provided with a bore 14, which has opening thereinto a lateral bore 60 15, and through which the cable 5 enters so as to lie in the bore 14. The cable is attached to the socket 16, said socket being mounted in the outer end of the bore 14. Detachably connected to the socket 16 is a 65 plug 17, which has leading therefrom circuit wires 18, said wires being in circuit with the batteries 19 and telephone 20, which are suitably mounted on the vessel. Thus it will be seen that when the plug 17 is engaged in the socket 16, that the circuit 70 through the wires 18 and cable 15 is closed, thereby lighting the lamps and placing the telephone 11 in circuit with the telephone 20. The float is provided with a closure 21, 75 which can be removed by the rescue crew so that access may be had to the telephone 20 mounted therein.

The float 10 is normally engaged in the holder 8, and is held therein through the 80 medium of the ratchet wheel 22, which has associated therewith a spring pressed pawl 23, said pawl serving to prevent rotation of the shaft 3, until the pawl has been actuated to disengage the ratchet wheel. The 85 shaft 3 has fixed to the end adjacent the ratchet wheel a crank handle 24, which serves to wind the cable 5 upon the drum 4. By slidably mounting the drum 4 upon the shaft 3, the same can move longitudinally 90 of said shaft when the float is rising, the cable meanwhile unwinding from the drum, whereby there will be a direct line of cable from the drum to the stuffing box 6.

From the foregoing description it will be 95 seen that should a vessel become disabled so as to not be able to rise to the surface under its own power, that the float 10 can be released so that same can rise to the surface to indicate the position of the disabled 100 vessel. To release the float, it is only necessary to rock the pawl 23 by placing the foot upon the extension 25 thereof, whereby the ratchet wheel will be released so as to permit the drum to rotate as the float rises. 105 It will be of course understood that the plug 17 is inserted in the socket after the float has reached the surface.

When it is desired to use the device for 110 locating sunken vessels, other than submarines, it is not necessary to equip the float with the telephone and lights, and the cable

is wound upon the drum in a reverse direction so that the pawl will act as a brake to prevent too rapid unwinding of the cable. It will be of course understood that the 8 electric cables can be incased in lead so as to prevent corrosion.

What is claimed is:—

10 A signal for submarine vessels comprising a holder mounted on the deck thereof, a float normally engaged in the holder, a shaft journaled within the vessel, a drum slidable on the shaft and rotatable therewith, an electric cable windable on the drum and having one end attached to the float, a socket 16 formed in one end of the shaft, the other end of said cable entering said socket, means

carried by the shaft for holding the same against rotation, whereby the float is positively held in the holder, incandescent lamps and a telephone mounted in the float, 20 batteries and a telephone mounted in the vessel, a plug insertible in the socket for closing the circuit through the batteries, telephone and lamp, and means for winding the cable on the drum.

25 In testimony whereof, I affix my signature, in the presence of two witnesses.

CHARLES F. NYQUIST.
